UNITED STATES PATENT OFFICE.

FRANCIS HERBERT OL德ROYD, OF RADCLIFFE, ENGLAND.

APPARATUS FOR PRODUCING KNOTTED PILE FABRICS.

Application filed May 5, 1927, Serial No. 189,065, and in Great Britain October 20, 1925.

This invention relates to apparatus for produced knotted pile fabrics, such as carpets and so forth, wherein the tufts are knotted to the foundation during the weaving 5 of the foundation.

In the said apparatus, means is provided for measuring off each tuft piece from a continuous length of yarn or the like preparatory to its separation from the said 10 length and insertion in the fabric.

My invention relates particularly to the said means and has for its main object to enable yarns or the like of all degrees of thickness or thinness, of all materials and of 15 all varying properties to be efficiently dealt with by the said means.

According to my invention the said means comprises a movable member provided with pairs of holding devices spaced distances 20 apart substantially equal to the required length of the tuft piece, each device of each pair being spaced a distance from the other device of the pair, whereby on movement of the said member the continuous length of 25 yarn passes successively into each holding device and is gripped thereby both before and after separation of the yarn between the holding devices of each pair.

The said means is preferably in the form of a rotatable hub provided with a plurality of pairs of arms the said pairs being spaced the required distance from one another at or near their extremities and the arms of each pair being also spaced apart a distance 30 sufficient to permit the passage of a yarn severing implement between them, and all of the said arms being provided with yielding grippers at or near their extremities to grip the yarn at places on both side of the 35 points of severance.

Each gripper preferably comprises a spring or yielding member acting in opposition to one or more surfaces to grip the yarn between it and the said surface or wedge 40 the yarn between it and the said surfaces.

In the accompanying drawings—

Figure 1 is a front elevation of a measuring-off means.

Figure 2 is a side view thereof.

Figure 3 is a front elevation of a detail and illustrates a modification.

Figure 4 is a plan view and

Figure 5 is a side view of Figure 3.

Referring to Figures 1 and 2 of the draw-

ings, in the construction shown therein, a 55 cylindrical hub 1 is adapted to be rotatably mounted on a stationary stud or spindle.

The cylindrical hub 1 has four pairs of flat tubular arms 2 attached to the hub 1 by members 3 engaging the arms 2 and slots 4 in the hub 1. The distance between each pair of arms 2 is equal and the whole therefore has an appearance somewhat similar to a maltese cross when regarded from the front. The arms 2 of each pair are also 60 spaced apart to leave a gap 5 between them for the entrance of a severing knife or other severing device. All the ends of the arms 2 are free and a radial gap or slot 6 is provided in each end each slot 6 having its 65 mouth situated in the end surface of its arm 2. The slots 6 are all in the same circular line.

A spring 7 of substantially inverted U shape is fixed in the interior of each arm 2 75 one limb of the spring 7 being situated towards the front of the arm and being gripped thereby and the other limb lying partly in the slot 6 and partly in the arm 2 at a place beneath the closed end of the slot 80 6. That part of the spring 7 which connects the said limbs together preferably lies beyond the extremity of the arm and is substantially parallel with the axis of the hub 1. The last named limb is free to yield and 85 is opposed to the rearmost side of the slot 6 which owing to the flat tubular formation of the arm 2 consists of two narrow surfaces separated by a space.

The mouth of each slot 6 is flared or 90 rounded off. For convenience of construction the front parts of the arms 2 may project axially beyond the hub in a forward direction. The corner of each spring 7 may be rounded where the parallel part joins 95 the free limb which extends radially into and past the closed end of the slot.

In operation the continuous length 8 of yarn or the like passes under tension through any suitable guide arranged in the 100 vertical plane which contains the radial centre lines of all the slots 6, and the end of the yarn or the like is pressed between the free limb of one of the springs 7 and the rearmost side of the corresponding slot 6. 105 The said end is thereby pressed or wedged by the spring 7 against the two surfaces forming the said side and between the said

surfaces, being thereby held firmly. Rotation of the whole in a direction in which the said slot 6 first moves away from the guide causes the yarn or the like to be drawn through the guide. The following slot 6 now moves into engagement with the yarn, which owing to the rounded parts of the slot 6 and spring 7 readily slips between the spring 7 and the rearmost side of the slot 6. The tension of the yarn causes it to be forced to the bottom of the slot 6 and the action of the spring 7 causes it to be automatically gripped in a similar manner to the said end. A part of the yarn now lies in a stretched, straight line between two of the arms 2. Further rotation causes the yarn to engage and be firmly held in the slot 6 of each succeeding arm 2. The yarn so held is now free to be severed by any suitable implement acting on the yarn between the arms 2 of each successive pair and when severance of the yarn at two adjacent pairs of arms 2 has taken place, a piece of yarn of the desired length for a tuft piece has been obtained but still remains firmly held by one arm 2 of each of two adjacent pairs in a straight, stretched state ready to be withdrawn from the slots 6 for insertion in the foundation being woven. The springs 7 whilst acting strongly to prevent the ends of the piece from moving in the direction of the length of the piece cause no undue resistance to a lateral withdrawal of the piece. As the severed pieces are removed, the slots 6 which held them become free and further rotation of the device again brings these slots 6 into action on the continuous length of yarn or the like to be engaged thereby and measure off further lengths ready for severance. The said slots 6 therefore repeatedly come into operation in a cycle.

The arms 2 thus repeatedly measure off pieces from the continuous length of yarn and hold them firmly in a stretched, straight condition both before and after severance until their ends are drawn outwardly or radially out of the slots 6, the number of pieces measured being determined only by the length of the supply of yarn or the like.

It will be appreciated that by varying the distance between the radial centre lines of the pairs of arms 2 any desired length of pieces can be obtained. Furthermore owing to the retention of a firm and positive hold on both ends of the yarn, the device acts with equal efficiency on any kind of yarn including springy yarn, whether doubled or not, on elastic yarn or yarn liable to curl, and on both thick, medium and thin yarns or even on thin wire. This feature, together with the perfect accessibility to the piece between its ends, facilitates the subsequent operation of knotting the pieces on the warp.

The device is preferably moved or rotated in an intermittent manner.

In the modification illustrated in Figures 3 to 5 each of the slots 4 of the boss 1 shown in Figures 1 and 2 has inserted in it a plate-like arm 9 having pivotally mounted on it at 10 a U-shaped jaw 11 adapted to co-act with a single jaw-like part 12 of the arm 9. The double jaw 11 is provided with a wing 13 which serves to secure a spring 14 to the oscillatable jaw 11. The spring 14 bears against the under side of a lug 15 provided on the arm 9. The single jaw 12 and double jaw 11 are flared or rounded at their opposed corners to facilitate the entry of the yarn between them. Figures 3 to 5 illustrate a pair of the plate-like arms 9 and it will be observed that the pivot pin 10 extends from arm to arm of the pair and serves as a pivot for both double jaws 11 of the pair. It will be understood that the gripping devices shown in Figures 3 to 5 when mounted on a hub in sufficient numbers operate in a similar manner to that described with reference to Figures 1 and 2.

I claim—

1. In apparatus for producing knotted pile fabrics a measuring means comprising a movable member provided with pairs of holding devices spaced distances apart substantially equal to the required length of the tuft piece, each device of each pair being spaced a distance from the other device of the pair, so arranged that on movement of the said member a continuous length of yarn passes successively into each holding device and is gripped thereby both before and after separation of the yarn between the holding devices of each pair.

2. A measuring means according to claim 1 and constructed in the form of a rotatable member provided with a plurality of pairs of arms, the said pairs being spaced from one another substantially at their extremities a distance corresponding to the required length of the tuft piece and the arms of each pair being also spaced apart a distance sufficient to permit the passage of a yarn severing implement between them and all of the said arms being provided with yielding grippers at or near their extremities to grip the yarn at places on both sides of the points of severance.

3. A measuring means according to claim 1 and constructed in the form of a rotatable member provided with a plurality of pairs of arms, the said pairs being spaced from one another substantially at their extremities a distance corresponding to the required length of the tuft piece and the arms of each pair being also spaced apart a distance sufficient to permit the passage of a yarn severing implement between them and all of the said arms being provided with yielding grippers at or near their extremities to grip the yarn at places on both sides of the points of severance, each gripper comprising a yield-

ing member and a surface against which said yielding member acts to grip the yarn therebetween.

4. A measuring device as claimed in claim 1, comprising plate like arms having oscillatable jaws mounted thereon and acted on in the closing direction by spring means.

5. In apparatus for producing knotted pile fabrics a measuring-off device comprising a movable member having mounted on it pairs of arms of which pairs each arm is parallel to the same radial plane, the said arms being

held in slots in the movable member and being provided with means to grip yarn firmly against displacement in the longitudinal direction of the yarn whilst permitting lateral movement thereof without detrimental resistance thereto. 15

In testimony whereof, I have signed my name to this specification at Manchester in the county of Lancaster, England, this 22nd day of April, 1927. 20

FRANCIS HERBERT OLDROYD.
